(57) **CLAIM**

The ornamental design for an explosion-proof light, as shown and described.

DESCRIPTION

FIG. 1 is a front, top left perspective view of an explosion-proof light showing my new design;

FIG. 2 is rear, bottom right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front elevational view of the explosion-proof light in a mounted position; and,

FIG. 10 is a side view of the explosion-proof light in another mounted position.

The broken lines in FIGS. 1-8 are included for the purpose of illustrating portions of the article which form no part of the claimed design. The broken lines in FIGS. 9 and 10 depict environmental structure and form no part of the claimed design.

1 Claim, 10 Drawing Sheets
